UNITED STATES PATENT OFFICE.

IRA SMITH, OF TOMHANNOCK, NEW YORK.

IMPROVEMENT IN HOISTING-MACHINES.

Specification forming part of Letters Patent No. 137,152, dated March 25, 1873.

To all whom it may concern:

Be it known that I, IRA SMITH, of Tomhannock, in the county of Rensselaer and State of New York, have invented a new and useful Improvement in Hoisting-Machines, of which the following is a specification:

The object of this invention is to furnish a cheap and simple machine for hoisting weights, for farmers' use, and other purposes; and it consists in the construction and arrangement of parts hereinafter described.

The drawing represents a side elevation, partly in section, of a machine constructed according to my invention.

Similar letters of reference indicate corresponding parts.

A is a projecting arm. B is the post, and C is the brace. These three parts are connected together, and the post is attached to the side of a building or other fixture by hinges D D, so that the arm will swing like the arm of the ordinary crane. E is the hoisting-wheel, supported by a shaft or arbor, F, near the outer end of the arm. The rim of this wheel is grooved, or lugs G are attached to the sides thereof to guide the hoisting belt or rope. In this example of my invention I employ a belt, H; but a rope or chain may be used instead of a belt. The power is applied to this belt either directly by hand or by means of the crank-pulley I, to which one end of the belt may be attached. The other end of the belt is attached

to the wheel L, around which it is wound, as represented in the drawing. J is a wheel on the arbor F, which revolves with the main wheel E. K is a belt or rope, which is wound around the wheel J as the main wheel is revolved. L is a grapple, which is attached to the article to be lifted.

The power applied may be greatly increased by means of the crank-wheel I, so that a small boy may raise a heavy weight.

This machine is constructed mainly of wood, and may be made by any one acquainted with the use of tools, as no cogged gearing is employed.

This machine may be employed in loading and unloading cars at railroad stations and vessels at the dock, as well as wagons at the farmer's door. It is cheaply made and easily repaired when out of order.

Having thus described my invention, I claim as new and desire to secure by Letters Patent—

A hoisting-machine consisting of the parts A, B, and C, wheels F and J, and belts or ropes H and K, with the crank-wheel I, when the same are combined and arranged to operate as and for the purposes described.

IRA SMITH.
